UNITED STATES PATENT OFFICE.

JAMES F. STRUBLE, OF HUTCHINSON, KANSAS.

WELL PUMP.

Application filed August 16, 1927. Serial No. 213,379.

This invention relates to water elevating devices for wells of the type in which a plurality of chain or cable carried pistons are utilized to draw the water from the well or 5 other reservoir upwardly through a suction tube to a discharge point.

One object of the present invention is to improve the operation of suction pumps of this general character by means relieving 10 the compression which occurs as the suction creating piston enters the base of the suction cylinder of the pump.

15 A further object of the invention is the improvement of the form and structure of the pistons or buckets, so-called, employed in this type of pump to create the water elevating suction. To this end a feature of the invention consists in a construction of piston providing a guiding means effective to center 20 and maintain the piston centered in the suction tube; also to so construct the piston as to provide for its economical manufacture and to facilitate replacement of the piston packing element thereof. These and other 25 objects and advantages will be more fully apparent from a reading of the following detailed specification in connection with the accompanying drawings forming part thereof and in which:

30 Figure 1 is a view in elevation of a chain pump embodying the improvements of the present invention installed in a well.

Figure 2 is a transverse vertical section through the pump as shown in Figure 1.

35 Figure 3 is a horizontal section on the line 3—3 of Figure 2 showing the pump cylinder support.

Figure 4 is a view in elevation of the bucket or piston chain wheel or sprocket mounted at the top and bottom of the pump casing.

Figure 5 is a vertical sectional view of the chain wheel as mounted on its journalling shaft.

45 Figures 6 and 7 are side elevations of opposite sides of the pump piston of the present invention, and, Figure 8 is a horizontal sectional view taken on the line 8-8 of Figure 7.

Referring to the drawings by numerals, 1 indicates a well or other reservoir opening, the top of which is partly closed by the slab 2 having a central opening for the upper pump cylinder section 3 and for the endless piston-carrying chain 4. The pump cylinder comprises the top and bottom sections 3 and

5 having ends tapered to a reduced diameter and joined to the intermediate or central suction cylinder 6. The bottom section 5 at its point of junction with the suction cylinder 6 may be shouldered to provide a smooth joint. The sections 3, 5 and 6, may be cast as one, although it is preferable to have them separate from the pump cylinder because of the varying depths of wells. 65

The bottom section 5 carries spaced depending arms 7 forming trunnions in which are journalled the ends of shaft 8 on which is keyed the hub 9 of a chain sprocket wheel 10. At the upper end similar brackets 11 extend upwardly from the upper end of pump section 3 and serve as journals for shaft 12 mounting chain sprocket wheel 13 and extended beyond a bracket at one end and provided with a crank handle 14 for operating. The arms, shafts and sprocket wheels, top and bottom of the cylinder are of identical construction. The upper section 3 of the pump is provided with a spout 15 and the pump sections with their attached sprocket wheels and the chain and piston buckets hereinafter described are supported from the top of the well by means of suitable bars 16 spanning the opening in slab 2 and carrying, by means of clamping bolts 17, opposed arcuate clamping blocks 18, which are drawn by the bolts firmly against and into clamping engagement with the upper section 3 of the cylinder.

The sprocket wheels 10 and 13 are of identical construction. A plurality of spokes 19 support a polygonal rim 20 whose sides are tangential to a circle concentric with the hub 9 and which are formed with a plurality of pairs of reversely directed chain link hooks 21, and with a piston receiving gap 22 located in the perimeter of the wheel between two groups of hooks 21. 11

The endless chain running over the sprocket wheels 10 and 13 comprises a series of alternating spaced outer and inner links 23 pivotally connected by pivot studs 24 inserted through spacing sleeves 25. The pistons hereinafter described occupy the space of one pair of links and are located on the endless link chain at uniform distances representing the perimetric length of the sprocket wheels or a multiple thereof. Obviously, the sprocket wheels are positioned to center the pistons and chain relatively to the pump cylinders 3, 5 and 6 as the chain and pistons enter and leave the cylinders. 100 105 110

In order to secure the maximum suction, the pistons should be centered in the cylinder 6 and in order that the pistons themselves give maximum service, their construction should combine simplicity with strength and a construction admitting of ready replacement of worn packing washers as well as emergency repairs.

I have therefore provided a construction of pump piston having these functions and advantages. The pistons are formed with circular heads 27 which may be of hardwood with chamfered edges, the diameter of the heads being slightly less than that of the suction cylinder 6. Downwardly tapering curved side pieces 28 which may be of pressed steel, have base flanges 29 by means of which they are rigidly secured at their base to the top face of the head. The sides 28 are curved to conform to the maximum diameter of the head and extend vertically upward from its edge. Their outer sides are faced with a sheet of leather or other appropriate material 28^a.

The head 27, centrally and at opposite sides has attached thereto bracket bases 31 with long upstanding spaced arms 32 at the upper side, and shorter depending spaced arms 33 at the under side of the head as viewed in Figures 6 and 7. These arms are spaced similarly to the inside links 23 and their ends are pivotally connected to the ends of outside links 23 of the chain by pivot studs 24 and spacing sleeves 25 such as are used in the chain itself. These studs also connect to the links, the upper ends of diagonal cross braces 30 riveted to the inside faces of the sides 28 and serving to brace and maintain these sides in permanently correct relation to the head 27 of the piston.

The distance between the chain-connected points of arms 32 and 33 is equivalent to the length of a chain link 23. To the chamfered edge of the head 27 is suitably attached a suction-producing packing strap 34 of leather or other suitable material having its abutting edges appropriately joined and held to the head by a metal strap 35.

The strap or packing 34 flares outwardly and extends to a point substantially above the top face of the head. It is normally of a maximum diameter greater than the internal diameter of the suction cylinder 6, and is pressed inwardly into tight engagement with the walls of the cylinder as it enters the cylinder through the tapered sides of the bottom section 5. As seen in Figure 1 of the drawings, the piston spacing sleeves 25 are engaged by the sprocket wheel hooks 21 at opposite sides of the pocket 22 with one side or half of the piston seating in the pocket.

The structure of the piston admits of ready replacement of the packing straps and

both the straps and head are subject to emergency replacement without waiting to obtain factory made parts. Since pumps of this character are almost universally used on farms which are frequently isolated, a construction permitting "home-made" repairs is especially advantageous. Strap leather for packing and hardwood suitable for shaping piston heads are practically always available. It is to be recognized, of course, that the head may be formed of material other than wood and that the head and sides may be cast or pressed of metal as a unitary structure.

As the pistons are drawn up through the lower cylinder 2 by the turning of the chain around the sprocket wheels through operation of crank handle 14, the sides 28 which are rigid with and perpendicular to the edge of the piston head first engage the sides of the suction cylinder 6 and automatically center the head of the piston relatively to the bore of this cylinder so that maximum contact is obtained and effective suction secured.

As the piston is drawn up through the converging portion of the lower cylinder 5, resistance to its entrance into the suction section 6 is offered by water or air or both which is caught between the sides of the piston and the tapering walls of the upper end of section 5, and is compressed as the piston enters into the suction portion 6 of the pump cylinder. To relieve this compression, I have provided a by-pass in the form of a tube connecting the interior of the section 6 at its point of junction with lower section 5, with section 5 preferably at a point below its tapered portion, and additionally, the sides of the lower end of the suction cylinder 6 in line with the pipe 36 are provided with a circumferential series of slots 37. Obviously, these slots are positioned below the water level of the well or reservoir, so as not to prevent water suction by the pistons.

The operation of a series of chain carried pistons of this general type to draw by suction, the water of the well or reservoir up cylinder 6 to the discharge point, is well known and need not be repeated.

The construction provided by the present invention not only improves the operation of the pump, but simplifies its construction and maintenance. The disclosed embodiments of my improvements are productive of the advantages heretofore recited, but may be varied in structure while maintaining the spirit and scope of the invention.

Having described the invention, what I claim and desire to secure by Letters Patent is:

1. In a pump, a cylinder having an upper suction section of one diameter and a lower section of greater diameter converging into a

- junction with said upper section, a piston having suction-creating packing arranged to engage the walls of the suction section, means for moving said piston upwardly 5 from the lower section into the suction section, and means located adjacent to the junction of the two cylinder sections for relieving the compression between the piston and the converging walls of the lower section adjacent 10 cent to said junction point.
2. In a pump, a cylinder having adjacent sections of small and larger diameter joined by converging walls, a piston of a diameter closely to fit the smaller cylinder section 15 having its packing engaging said converging walls adjacent to the section junction point, and a compression releasing opening in the cylinder wall adjacent to said point.
3. In a well pump, a cylinder having an 20 upper suction section of one diameter and a lower completely immersed section of greater diameter with walls converging into a junction with the upper section, a piston formed closely to engage the walls of the 25 first section and with its packing engaging said converging walls adjacent to said junction and creating compression between piston and wall, and a plurality of compression relieving openings in the cylinder wall adjacent 30 to said junction point.
4. In a well pump, a cylinder having an upper suction section of one diameter and a lower completely immersed section of greater diameter with walls converging into a junction 35 with the upper section, a piston formed closely to engage the walls of the first section and with its packing engaging said converging walls adjacent to said junction and creating compression between piston and 40 wall, the walls of said cylinder having compression relieving slots formed therein adjacent to said junction point.
5. In a well pump, a cylinder having an upper suction section of one diameter and a lower completely immersed section of 45 greater diameter with walls converging into a junction with the upper section, a piston formed closely to engage the walls of the first section and with its packing engaging said converging walls adjacent to said junction and creating compression between piston and wall, and a compression relieving 50 by-pass connecting the interior of the cylinder between a point adjacent to said junction and a point in the lower cylinder substantially below said junction.
6. In a well pump, a cylinder having an upper suction section of one diameter and a lower completely immersed section of greater 55 diameter with walls converging into a junction with the upper section, a piston formed 60
- closely to engage the walls of the first section and with its packing engaging said converging walls adjacent to said junction and creating compression between piston and wall, and a compression relieving by-pass connecting the interior of the cylinder between a point adjacent to said junction and a point in the lower cylinder substantially below said junction with a circumferential series of compression-relieving slots in said cylinder wall at said junction point.
7. In a suction pump, a cylinder having a central suction section and top and bottom enlargements converging into said suction 65 section and having supporting guides, an endless carrier mounted over said guides and alined thereby to pass centrally through the bore of the cylinder, a plurality of pistons on said carrier in determinate spaced relation, one of said pistons having a circular head mounting peripheral packing and having alined arcuate side portions positioned to engage the cylinder walls in advance of the head to center the head in the bore of the 70 cylinder.
8. A pump piston comprising a circular disk with peripherally alined side guides extended upwardly therefrom and periphery attached packing.
9. A pump piston comprising a circular disk with chamfered peripheral edge and having attached thereto and extending upwardly therefrom peripherally alined side guides, and strap packing secured to and extending beyond said chamfered edge.
10. A pump piston comprising a solid circular head of wood with chamfered peripheral edge, arcuate side pieces rigidly attached to a face of the head and alined with the periphery thereof, strap packing secured to and extending beyond said chamfered edge, and brackets secured to opposite faces of the head centrally thereof, and having attaching arms extending outwardly and oppositely from the head and substantially perpendicular thereto.
11. A pump piston for chain pumps, comprising a solid circular head with chamfered peripheral edge and arcuate peripherally alined side guiding faces, packing attached to said edge of the head, brackets secured to opposite faces of the head centrally thereof and having pairs of spaced chain link arms extending outwardly and oppositely from the head in perpendicular relation thereto and formed for attachment to the cross links of chain-link sections, and cross braces extending from said side faces to a pair of said link arms for connection therewith to a cross link.
